TRACING IMPLEMENT

Sidney O. Orthwin, Dayton, Ohio

Application September 9, 1954, Serial No. 32,230

Term of patent 14 years

(Cl. D3—19)

To all whom it may concern:

Be it known that I, Sidney O. Orthwin, a citizen of the United States, residing at Dayton, in the county of Montgomery and State of Ohio, have invented a new, original, and ornamental Design for a Tracing Implement, of which the following is a specification, reference being had to the accompanying drawing, forming a part hereof.

Fig. 1 is a perspective view of a tracing implement showing my new design;

Fig. 2 is a side view thereof;

Fig. 3 is a top view; the bottom thereof being identical in appearance;

Fig. 4 is a longitudinal sectional view taken along the line 4—4 of Fig. 2;

Fig. 5 is a sectional view taken on the line 5—5 of Fig. 2; and

Fig. 6 is a sectional view taken on the line 6—6 of Fig. 2.

I claim:

The ornamental design for a tracing implement, as shown.
